Inventor:

Robert B. Fliegner

UNITED STATES PATENT OFFICE.

ROBERT B. FERGUSON, OF LOS ANGELES, CALIFORNIA.

TRUNK-FASTENER.

1,077,195.

Specification of Letters Patent.

Patented Oct. 28, 1913.

Application filed September 23, 1912. Serial No. 721,997.

To all whom it may concern:

Be it known that I, ROBERT B. FERGUSON, a citizen of the United States, residing at the city of Los Angeles, in the county of 5 Los Angeles and State of California, have invented new and useful Improvements in Trunk-Fasteners, of which the following is a specification.

My invention relates to that class of trunk 10 fasteners in which chains or ropes are provided and adapted to encircle the trunk so that by means of a tension device the chain or rope may be properly strained, and the object thereof is to provide a cheap, simple, 15 and efficient device for that purpose which can be locked in its operative position. I accomplish this object by means of the device described herein and illustrated in the accompanying drawings forming a part 20 hereof in which—

Figure 1 is a top plan view of a trunk showing the device in position ready to strain the chain, with the device dotted in its closed position. Fig. 2 is an enlarged 25 top plan view of my device in its locked position. Fig. 3 is a side elevation of Fig. 2.

In the drawings 5 is an L-shaped body member, preferably a brass rod the ends of 30 which are flattened. One portion 6 of the body is shorter than the other and will be called the short end and the other portion will be called the long end of the body. A tensioning lever 8 has a slot 7 in one end thereof and is pivotally mounted by pintle 35 bolt 9 upon the short end 6 of the body. A locking clevis 10 is pivotally secured to the long end of the body by pintle bolt 11. Near the clevis a retaining pin 12 is mounted in the body 5. Secured to the tensioning 40 lever 8 near its connection to member 6 is a stud 13 to which is pivotally secured a clevis 14 by a pintle bolt 14^a. Clevis 14 straddles lever 8, and surrounds the same. One end of chain 17 is secured upon clevis 45 14. A recess 15 may be provided in lever 8 into which will be received the end of pin 12 when the parts are positioned for use.

In the operation of my device the chain is first placed to encircle the trunk 18 with 50 the body member and tensioning lever preferably on the top in the position shown in Fig. 1. The loose end of the chain is then threaded through clevis 10 and drawn as tight as possible by hand. A link is then 55 slipped over retaining pin 12. The tensioning lever 8 is then turned on its pivot

to a position parallel with lever 5 which tightens the chain securely around the trunk. In passing to this position the end of stud 12 is received in a recess 15 provided 60 in lever 8. Locking clevis 10 is then rotated on its pivot to encircle the end of the tensioning lever. The hasp of a padlock 16 is then threaded through clevis 10 between the outer end of said clevis and the operating 65 lever and locked, thus preventing clevis 10 from being drawn off the tensioning lever. The outer end of lever 8 is preferably curved outwardly slightly as best shown in Fig. 2, to more securely position 70 the lock. It will be seen from the relative positions, one with the other, of pintle bolts 9 and 14^a that the device when closed will always tend to remain so whether or not the locking clevis is encircling the tensioning 75 lever.

Having described my invention what I claim is:—

1. A trunk fastener comprising an L-shaped body member one end of the L being 80 longer than the other; a locking clevis pivotally connected to the longer end of the body; a pin mounted in the body near the locking clevis and projecting therefrom on the same side as the shorter end of the body; 85 a tensioning lever pivotally connected to the shorter end of the body of a length substantially the same as the longer end of the body; a stud mounted in the tensioning lever near its connection with the body and 90 projecting toward the longer end of the body when positioned for use; a clevis surrounding said lever and pivotally connected to the stud mounted in the lever; and a chain mounted on the clevis surrounding 95 the lever, said chain being adapted to be passed around a trunk and through the clevis at the longer end of the body and secured upon the pin therein and then tensioned by the lever. 100

2. A trunk fastener comprising an L-shaped body member, one end of the L being longer than the other; a locking clevis pivotally connected to the longer end of the body; a pin mounted in the body near the 105 locking clevis and projecting therefrom on the same side as the shorter end of the body; a tensioning lever pivotally connected to the shorter end of the body of a length substantially the same as the longer end of the 110 body; a stud mounted in the tensioning lever near its connection with the body and

projecting toward the longer end of the body when positioned for use; a clevis surrounding said lever and pivotally connected to the stud mounted in the lever; a chain mounted on the clevis surrounding the lever, said chain being adapted to be passed around a trunk and through the clevis at the longer end of the body and secured upon the pin therein and then tensioned by the lever; in combination with a locking means

to hold the locking clevis on the tensioning lever.

In witness that I claim the foregoing I have hereunto subscribed my name this 10th day of September, 1912.

ROBERT B. FERGUSON.
